UNITED STATES PATENT OFFICE.

HERBERT S. ATKINSON, OF WEEHAWKEN, NEW JERSEY, ASSIGNOR TO HAYWARD COMPANY,
A CORPORATION OF NEW YORK.

CHAIN.

No. 889,170.

Specification of Letters Patent.

Patented May 26, 1908.

Application filed September 16, 1907. Serial No. 392,988.

To all whom it may concern:

Be it known that I, HERBERT S. ATKINSON, a citizen of the United States, and a resident of Weehawken, in the county of Hudson and State of New Jersey, have invented certain new and useful Improvements in Chains, of which the following is a specification.

In the operation of dredging buckets of 10 the types commonly known as "clam-shell" and "orange peel", it is customary to employ, among other mechanism, a chain for the opening and closing mechanism, such chain being wrapped about a wheel or drum 15 upon a shaft connecting the bucket sections. Heretofore, at times difficulty has been experienced in the operation of these buckets because the chains in wrapping or coiling one section upon the other, had a tendency to 20 entangle.

Among other purposes, therefore, I aim to devise a chain formed of a plurality of sections so connected and arranged one section 25 relative to the other, that in the wrapping or winding of the chain around a shaft or drum the sections will not overlap but will lie one between the other. However, I do not wish to be limited to the particular use described for my chain as it is my purpose, first to provide a chain useful for many purposes and 30 one which will embody the desired features of simplicity and durability.

In the accompanying drawings like characters of reference indicate like parts in all the 35 views.

Figure 1 is a view in side elevation of a chain embodying my improvements; Fig. 2 is a view in front elevation; Fig. 3 is a plan view of one of the lower terminal links, which 40 link is designed to be connected by a pin or the like with a bucket or other article; Fig. 4 is a plan view of one of the intermediate links going to make up the chain; Fig. 5 is a plan view of a single link; Fig. 6 is a plan view of 45 the hanger link by means of which the chain may be suspended from any suitable point; Figs. 7 and 8 illustrate modifications of my invention.

Referring now to the accompanying drawings in detail and especially to Figs. 1 and 2, A indicates one section of the chain, which 50 may be considered as a single section, and B indicates a second section of the chain which may be considered as a double or duplex section, the two members 5, 5 of this double

duplex section being suspended from the pin 7 passing through the sleeve bar 8 carried by one end of the section A, said sleeve acting as a spacer for the two members, 5, 5 of the section B. This sleeve bar spaces the two sections 5, 5 apart a suitable distance so that when the chain is coiled or wrapped the section A may occupy the space between the section 5, 5, thereby obviating the overlapping of the wraps of the chain. 60

One of the sections, for instance, the single section A, is provided with a suitable suspender or hanger 9 provided with an opening 10 for the passage of the suspending pin. The chain sections A and B are formed of a 70 plurality of individual links 11 and 12, the link 12, which is the center link, lying between the two side links 11, and is connected therewith by a pintle 13 in the well known manner. The numeral 14 indicates a terminal link having an opening 15, this link 14 being designed to be connected to a bucket or the like. 75

In Fig. 7 I have shown a modified form of chain, in this case the section A' is connected, 80 in the manner heretofore described, with two members of the section B', each of these members in turn carrying a sleeve bar 8^a through which passes the pin 7^a and from which pin is suspended in turn two chain sections C'. 85

In Fig. 8 I have shown a further modification; in this case three chain members D', D', D', are suspended from the pin 7^b.

In all the constructions shown I embody a 90 chain, which, as heretofore described, may be coiled or wrapped in a manner to avoid the overlapping of the chain members when coiled about a drum or shaft.

What I claim is:

1. A chain formed of a plurality of connected sections, one of said sections being locked to an adjacent connected section so that it lies between the members forming the adjacent section when the chain is coiled or 100 wrapped.

2. A chain formed of a plurality of sections, a sleeve bar carried by one of said sections, a pin passing through said sleeve bar and a plurality of chain members forming 105 the next or adjacent section, connected to said pin and held spaced apart by the sleeve bar.

3. A chain comprising a plurality of sections, a spacing device carried by one of said 110

sections, and a plurality of chain members forming an adjacent section, connected to the first section and held spaced apart by a spacing device to permit the first mentioned section to lie between the members forming the second section.

4. A chain comprising a suspender link, a chain body formed of a plurality of connected links joined to the suspender link, a spacing bar sleeve connected at approximately the

center to the chain body, and a plurality of chain bodies forming the next section held spaced apart by the spacing bar sleeve.

In testimony whereof I have hereunto signed my name to this specification in the presence of two subscribing witnesses.

HERBERT S. ATKINSON.
